UNITED STATES PATENT OFFICE.

MICHAEL J. SHANLEY, OF BROOKLYN, NEW YORK.

CLOTHESLINE SUPPORT.

Application filed May 27, 1924. Serial No. 716,179.

To all whom it may concern:

Be it known that I, MICHAEL J. SHANLEY, a citizen of the United States of America, and a resident of the city of New York, 5 borough of Brooklyn, in the county of Kings and State of New York, have invented a new and Improved Clothesline Support, of which the following is a description.

My invention relates to a device for supporting a clothesline and particularly to a clothesline support in which an arm is provided carrying a pulley, over which the line runs, the arm being swingable into a room from the outside of a window for the convenient hanging of the clothes, the arrangement being such that the person hanging the clothes has firm footing within the room and the danger of being pulled through the window is eliminated.

10 The general object of my invention is to provide a device for the indicated purpose improved in various particulars with a view to promote convenience in the manipulation of the device, and to facilitate the hanging and removal of the clothes with safety, as well as to provide for a firm holding of the pulley arm when the same is swung into the room and the clothes are being hung on the line.

15 The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a partly sectional plan view of a clothesline support embodying my invention, illustrating the same applied to a window frame shown in part in horizontal section;

Figure 2 is a partly sectional side elevation of the device as mounted on the window frame;

Figure 3 is a front elevation of the clothesline support in lowered position;

Figure 4 is an elevation of the inside bracket for firmly sustaining the pulley carrying arm when in the raised position and swung into the room.

In carrying out my invention in accordance with the illustrated example an arm 10 is provided made in practice of standard pipe and of a length to extend from outside

of a window frame A through the window and to project into the room. Said pipe 10 at its inner end is carried by a vertical T-head 11 formed of two short lengths of pipe united by a fitting 12 which is secured to the 60 arm 10. The T-head 11 is provided at the top and bottom with caps 13.

On the outer end of the arm 10 is a cap 14 having a central hole in which is swivelled a hook 15 adapted to receive the frame 16 65 of a standard pulley 17, over which the clothes line B runs. The hook is deflected or bent so that the end or bill of the hook is disposed toward the inner end of the arm 10.

On the T-head 11 turns an idler pulley 70 18 about which the upper run of a clothesline B extends when the arm 10 is horizontally disposed within the room and onto which both runs of the line B may be disposed when the arm 10 is in the lowered 75 position as in Figure 3.

The T-head 11 is pivotally supported in a bracket 19 which is secured to a fixed bracket 20 on the window frame A by a slot and pin connection, there being a pin 21 on said bracket 20 and a longitudinal slot 22 in bracket 19 at the end opposite that supporting the arm 10. The slot and pin connection permits of the bracket 19 carrying the head 11 and arm 10 turning about the axis of the pin 21 and moving longitudinally relatively to said pin 21 and the bracket 20. On the fixed window bracket 20 is an extension 120 having a terminal flange 23 formed with a vertical slot 24 in 90 which slot the bracket 19 may be engaged when the arm 10 is in the raised position as indicated in dotted lines in Figure 3 and in full lines in Figures 1 and 2.

In order to afford firm support to the arm 95 10 in the raised position, I provide in addition to the bracket 19 at the outside of the window frame A an inside bracket 25 which is formed as best seen in Figure 4 with a depression 26 in which the arm 10 100 when raised is adapted to seat. The inside bracket 25 is slidably and turnably mounted on the window frame A at the inside by means of a plate 27 fixedly secured to the inner face of the window frame by screws 105 or the like and provided with a stud or pin 28 which extends through a keyhole slot 29 in bracket 25. The pin 28 when in the elongated portion of the slot 29 permits of turning and sliding movement of bracket 25 110

and the enlarged end of slot 29 permits of the head 11 passing therethrough for detaching bracket 25 when not required. In the horizontal raised position of the bracket 25, the same is adapted to engage a lug 30 on plate 27, said lug being received in a notch 31 in bracket 25.

With the described arrangement the arm 10 may be lowered by lifting it from the depression 26, the head 11 being capable of a turning movement in the outer end of the outside bracket 19. Said bracket 19 after it has been detached from the slot 24 in member 23 of the fixed window bracket 20 and said bracket 19 then moved by reason of the slot and pin connection to a depending position as shown in Figure 3, positions the head 11 and arm 10 as well as the pulley 17 disposed suspended on said bracket 19.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A clothesline support including an arm, a T-head on said arm, a pulley carried by the arm adjacent the outer end, an idler pulley on said T-head, a bracket in one end of which said T-head is mounted, a second bracket adapted to be fixedly secured to a window frame, a pivotal connection between

said brackets to permit the first bracket to swing to approximately horizontal position or to a pendent position, and a member in fixed relation to the second-mentioned bracket and adapted to afford support for the first bracket when in the raised horizontal position.

2. A clothesline support including an arm, a T-head on said arm, a pulley carried by the arm adjacent the outer end, an idler pulley on said T-head, a bracket affording the turnable support for said T-head, means pivotally mounting said bracket, means to support said bracket in the raised position, the bracket when disengaged from said supporting means being adapted to swing on its pivotal connection to a pendent position to suspend the arm, and a bracket adapted to be secured to a window frame distant from the first bracket to afford support for said arm when in the raised position.

3. A clothesline support including an arm, a pulley carried by the arm adjacent the outer end, a T-head on said arm at the inner end, a bracket mounting at one end thereof the said T-head, means to pivotally mount said bracket on the outside of a window frame so that the arm and T-head may turn with said bracket to positions with the arm raised to a horizontal position or to dispose the arm and T-head pendent from the bracket, and means to engage said bracket to hold the same in position with the arm horizontal.

MICHAEL J. SHANLEY.
